The ornamental design for a nonwoven fabric, as shown and described.

DESCRIPTION

FIG. 1 is a top plan view of a nonwoven fabric showing our new design; and,

FIG. 2 is an isometric view thereof.

The outer broken line boundaries in FIGS. 1-2 depicting the boundaries of the claimed design; indicate that a specific length and width form no part of the claimed design, and are for illustrative purposes only, forming no part of the claimed design. The pattern repeats uniformly throughout the length and width of the fabric.
